CLAIM

The ornamental design for a pair of sandals, as shown and described.

DESCRIPTION

FIG. 1 is a bottom view of a pair of sandals showing my new design.

FIG. 2 is a right side view of a pair of sandals

FIG. 3 is a left side view of a pair of sandals.

FIG. 4 is a plan view of a pair of sandals.

FIG. 5 is front view of a pair of sandals; and,

FIG. 6 is a back view of a pair of sandals.
